UNITED STATES PATENT OFFICE

2,486,492

VENETIAN BLIND

Harold M. Redman, Pontiac, Mich.

Application August 16, 1946, Serial No. 691,049

2 Claims. (Cl. 160—173)

1

This invention relates to Venetian blinds of the type having a drop bar and a head structure in which means is provided for lifting and collapsing the slat arrangement and structure interposed between these parts, the principal object of the invention being to provide novel means for fastening the usual lift cords to the drop bar in such a manner as to permit quick detachability of the lift cords from the drop bar and displacement of the lift cords entirely from the slats so that the slats can be readily removed for the purpose of cleaning or painting.

Another important object of the invention is to provide a new form of drop cord fastening means for Venetian blinds which will permit quick disassembling of the Venetian blinds, even by house-holders, when it is desired to clean the slats thereof or make incidental repairs.

A further object of the invention is to provide an improved Venetian blind construction which has the advantages above asserted and without noticeably increasing the cost of manufacture.

These and other objects and advantages of the invention will become apparent to the reader of the following description.

In the drawings:

Figure 1 is fragmentary front elevational view of the lower left hand corner of a Venetian blind with a portion broken away to disclose the improved fastening means for the corresponding pull cord.

Figure 2 is a fragmentary vertical sectional view taken on line 2—2 of Figure 1.

Figure 3 is a fragmentary vertical sectional view also substantially taken on line 2—2 of Figure 1, but showing the guide feature of the pull cord fastening means elevated to a position freeing two of the slats.

Figure 5 is a perspective view of the slotted detent washer for the guide.

Referring to the drawing, numeral 5 denotes the usual base or drop bar of a Venetian blind structure, the blind being slightly modified over conventional construction to accommodate the present invention, which is generally referred to by numeral 6.

Numerals 7, 8 denote the usual front and rear tapes, connected by horizontal slat supporting tapes 9, upon which horizontal slats 10 of the usual shape and material are supported.

Each of the slats 10 at the points where drop cords 11 extend therethrough are formed with over-sized openings 12, matching like openings 13 in the horizontal slat supporting tapes 9.

For each pull cord 11, the drop bar 5 has a 55

2

circular opening 14 therein for snugly receiving the corresponding guide element 15 of the fastening means 6.

The guide 15 is in the form of a cylindrical plug having a diametrically disposed and longitudinally extending slot 16 therein, opening through the ends thereof and adjacent the lower end of the guide 15 are chordal slots 17 on diametrically opposite sides thereof and in substantially parallel relation with the slot 16.

The slot 16 is preferably somewhat narrower than the diameter of the cord 11, so that some force must be exerted in disposing the lower end of the cord to the proper position within the slot 16, after which brads or other fastening elements 18 can be driven into the guide 15 so as to pierce the cord and hold the cord against slipping from the guide.

As is fairly shown in Figures 1, 2 and 3, the opening 14 merges with a much larger counter-bore or recess 19 into which the lower end of the guide 15 depends when in fastened position.

To prevent displacement of the guide 15 from the drop bar 5, a disc or washer 20 is employed, 25 this washer having a diametrically formed slot 21 for embracing the reduced portion of the guide 15 at the slot 17, with the edge portions of the washer 20 at the opening 21 disposed through the chordal slot 17, 17, the washer bearing against the top of 30 the counter-bore 19, thus interlocked with the guide 15 to prevent displacement of the guide from the drop bar 5. With the washer 20 in place on the guide 15, the lower end of the guide terminates substantially flush with the bottom 35 of the drop bar 5 or somewhat within the counter-bore 19.

In the use and operation of the structure above set forth, and assuming that the parts are assembled as shown in Figure 1 and 2, in order 40 to remove the slats 10 for the purpose of cleaning or painting, the guide 15 is first forced downwardly in the opening 14 of the drop bar 5 so that the slotted washer 20 is exposed below the counter-bore 19, in which position the washer can 45 easily be removed from the guide 15. The pull cord 11 can now be grasped, for instance above the lowermost slat 10, to pull the guide 15 upwardly from the drop bar 5 and through the lowermost slat 10 and successively the guide 15 can be pulled through the openings 12, 13 of the slats 10 and cross-tapes 9 until all of the slats 10 have been freed. The slats can now be pulled laterally from the blind structure and cleaned, painted or otherwise renovated. After the slats

50 have been properly treated, they are reinserted

between the front and rear tapes 7, 8 until the openings 12, 13 register, after which the guide 15 can be threaded downwardly through the slats and cross-tapes 9 and finally through the opening 14 of the drop bar 5, to a position with the chordal slot 17 accessible below the drop bar 5 when the slotted washer 20 can be disposed in position as shown in Figures 1 and 2, after which the guide 15 is pulled upwardly so that the washer 20 bears against the top of the counter-bore 19.

While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

1. In a Venetian blind, a drop bar, slats above the drop bar formed with aligned openings, and a pull cord passed vertically through the aligned openings, said drop bar being formed with an opening leading from its upper face and with a counter-bore in its under face with which its opening communicates, a stiff sleeve formed with a longitudinally extending radially disposed groove into which the lower portion of the pull cord fits and is secured against displacement, said sleeve passing snugly through the opening in the drop bar and into the recess thereof and within the recess being formed with chordal grooves disposed at opposite sides of the longitudinally extending groove, and a washer formed with a radially extending slot and straddling the sleeve transversely thereof with portions of the washer at opposite sides of its slot fitting tightly in the transverse grooves of the

sleeve, said washer removably fitting within the recess of the drop bar with portions projecting laterally from the sleeve and bearing against the top of the recess and serving to prevent upward movement of the sleeve through the opening in the drop bar.

2. A device for preventing upward movement of a pull cord through an opening in a drop bar of a Venetian blind, said device comprising an elongated member of a diameter adapting it to pass through an opening in a drop bar, said member being formed in a side portion with a radially disposed groove extending the full length of the said member and in which a lower portion of a pull cord is adapted to fit, portions of the said member at opposite sides of said groove being formed with transversely extending grooves in opposed relation to each other, and a disk formed with a slot leading from its marginal edge, said disk being removably applied to the said member with portions at opposite sides of its slot engaged in the transverse grooves of the said member and the portion of the said member between its transverse grooves fitting into the slot of the disk.
